US00D827922S

(12) **United States Design Patent** (10) Patent No.: **US D827,922 S**
(45) Date of Patent: ** Sep. 4, 2018

(54) **ELECTRONIC VAPORIZER**

- (71) Applicant: **Altria Client Services LLC**,
Richmond, VA (US)
- (72) Inventors: **Eric Hawes**, Glen Allen, VA (US);
Traci Martin, Richmond, VA (US);
Melissa Burroughs, Richmond, VA
(US); **Berina Yerkic-Husejnovic**,
Richmond, VA (US); **Raymond Lau**,
Richmond, VA (US); **Christopher S.**
Tucker, Midlothian, VA (US); **Anthony**
Dibitonto, Richmond, VA (US); **Marc**
Sauriol, Richmond, VA (US); **George**
Stafford, Richmond, VA (US); **Jamie**
Nicholson, Richmond, VA (US); **Mark**
Breneman, Richmond, VA (US);
Alistair Bramley, Richmond, VA (US)
- (73) Assignee: **Altria Client Services LLC**,
Richmond, VA (US)
- (**) Term: **15 Years**
- (21) Appl. No.: **29/616,782**
- (22) Filed: **Sep. 8, 2017**

CLAIM

The ornamental design for an electronic vaporizer, as shown and described.

DESCRIPTION

FIG. 1 is a perspective view of an electronic vaporizer; FIG. 2 is another perspective view of the electronic vaporizer;

FIG. 3 is a top view of the electronic vaporizer;

FIG. 4 is a bottom view of the electronic vaporizer;

FIG. 5 is a first side view of the electronic vaporizer;

FIG. 6 is an opposite side view of the first side view of the electronic vaporizer;

FIG. 7 is a front view of the electronic vaporizer; and,

FIG. 8 is a rear view of the electronic vaporizer.

In the drawings, the broken lines depict environmental subject matter only and form no part of the claimed design. The claimed design extends to the boundary, but does not include the boundary.
